HYDROXY SULPHONATED FATTY ACID
ESTERS AND THEIR PRODUCTIONCharles C. Clark, St. Bernard, Ohio, assignor to
The Procter & Gamble Company, Cincinnati,
Ohio, a corporation of OhioNo Drawing. Application July 6, 1933, Serial
No. 679,217

10 Claims. (Cl. 260—106)

This invention relates to new foaming, emulsifying, wetting and cleansing agents comprising substances having the general molecular structure of derivatives of glycerol in which one of the hydroxyls is esterified with a higher fatty acid, one remains unchanged, and the third is replaced by the SO_3M group, where M may be a metal or other basic radical. Such compounds may also be considered as salts of sulphonated monoglycerides of fatty acids.

The objects of the invention are to provide new and useful compounds having the desirable properties above mentioned, and to provide means for producing same.

It is known that foaming, emulsifying, wetting and cleansing properties are possessed by sulphate esters of certain oils, fats, waxes, fatty acids and fatty alcohols, and that such properties are also possessed by the salts of certain sulphonic acids, such, for example, as those which can be prepared by esterifying the alkali metal salts of isethionic acid with fatty acids. It is also known that compounds with similar properties can be prepared by combining such products as the sodium salt of 1,2-hydroxy propane sulphonate acid, or the sodium salt of 1,3-hydroxy propane sulphonate acid with fatty acids or fatty acid chlorides. I make no claim to such compounds, which do not contain a free hydroxyl group in the nucleus of the molecule.

I have found that a new class of compounds, of different structure from the above, but possessing the above-mentioned desirable properties to a remarkable degree, can be prepared by causing salts of glycerol alpha-sulphonate acid to react with a higher saturated or unsaturated fatty acid or fatty acid halide, thereby obtaining the mono-fatty acid ester, or a mixture of the mono- and the di-fatty acid esters, of the said salts of glycerol alpha-sulphonate acid. I have also found that the mono-fatty acid ester of an alpha-glycerol sulphonate, possessing a free hydroxyl group in the nucleus of the molecule, has the desirable foaming, emulsifying, wetting, cleansing and dispersing properties to a greater extent than has the di-fatty acid ester or a mixture of the mono- and the di-fatty acid esters, and that a separation of the relatively more desirable mono-fatty acid ester from the relatively less desirable di-fatty acid ester can be effected by washing with, or preferably by crystallization from ethyl alcohol or other low-boiling alcohol. Such separation is sometimes desirable, but is not in all cases essential, and my invention is not limited to the purified product obtained by such separation.

The purified product so obtained is characterized by a molecular nucleus of three carbon atoms, to one of which a free hydroxyl group is attached, to another of which a higher fatty acid radical is attached by an ester linkage, and to the third of which the salt of a sulphonate acid group, SO_3M , is attached, the sulphur of this last mentioned group being combined directly with the terminal carbon atom of the said nucleus. The product so obtained is of the general formula: $\text{XCH}_2\text{CHYCH}_2\text{SO}_3\text{M}$, where M may be any alkali metal, alkaline earth metal, heavy metal, ammonium or basic organic radical which, in the above combination, is soluble in water, and where X may be a fatty acid radical, in which case Y is a hydroxyl group, or else X may be a hydroxyl group in which case Y is a fatty acid radical. The alkali metals and magnesium form especially useful products, but it should be understood that any metal or basic radical that forms water-soluble compounds may also be used. The fatty acid radical in either case may be any saturated or unsaturated fatty acid radical having six or more carbon atoms in the molecule. Products of this type differ from previously used fatty acid esters of sulphonate acids in that they possess an alcoholic hydroxyl group in the nucleus of the molecule, and this alcoholic hydroxyl group has been found to add greatly to the solubility of the compound in water and to render it especially useful in hard waters. Thus the replacement of this hydroxyl group by hydrogen or by a higher fatty acid group lessens the foaming emulsifying, wetting and cleansing power of the product and its solubility in hard waters.

It is understood that in making the products of my invention, in place of a single fatty acid a mixture of fatty acids may be used, such for example as occurs in any of the natural fats or oils; likewise a mixture of metals or basic radicals may be used in place of a single one. The fatty acids from cocoanut oil or palm kernel oil are especially suitable in making my products.

The products of my invention may be made by means of several different reactions depending on the nature of the starting materials. One method is to start with a soluble salt, such for example as the sodium salt of glycerol sulphonate acid (sodium 1,2-dihydroxy propane-3-sulphonate, prepared by heating alpha chlorohydrin with aqueous Na_2SO_3 solution and subsequent removal of water) and cause it to combine with the desired fatty acids. This is accomplished by heating one molecular proportion of the afore-

mentioned salt with one molecular proportion of the fatty acid in a suitable reacting chamber equipped with a reflux condenser. For the best yields, the mixture must be heated with stirring 5 to a temperature ranging from about 150° to 225° C. for a period of about 5 to 10 hours. The water formed in the reaction is allowed to escape while any fatty acids which volatilize are returned to the reacting chamber by the reflux 10 condenser.

A second method is to start with the same form of salt of glycerol sulphonic acid and heat same with a fatty acid chloride instead of a fatty acid itself. In this case again, equal molecular quantities are used and the process is similar except that it proceeds at a much lower temperature, such as from approximately 75° to 125° C., for a period of about 5 to 10 hours. The hydrochloric acid formed in the reaction is allowed 15 to escape, but any acidity still remaining at the end of the reaction should be neutralized with caustic soda or other basic reagent.

A third method is to start with a soluble salt, such for example as the sodium salt, of 1-chloro-25 2-hydroxy propane-3-sulphonic acid and heat same as above with an alkali soap of a fatty acid. In this case, a temperature of about 100° to 200° C. is required with stirring for about 5 to 10 hours.

30 All three of these methods will yield products of the same chemical structure and properties, differing only in the nature and amount of the impurities which may be present as a result of the method used. The first and second methods, for example, may result in the presence, as impurities, of fatty acids or of the sodium salt of glycerol sulphonic acid, while the second and third methods may result in the presence, as impurities, of alkali metal soap or of sodium chloride 35 besides unacted-on materials. In the case of the third method, there may also be present unreacted sodium salt of 1-chloro-2-hydroxy propane-3-sulphonic acid. The reaction products may in all cases be purified sufficiently for 40 practical purposes by washing with cold ethyl alcohol or other low-boiling alcohol, or preferably by dissolving in hot ethyl alcohol, filtering to remove insoluble salts and other matters, and crystallizing from the alcoholic solution. The product thus obtained will consist essentially of the mono-fatty acid ester, substantially free from the di-fatty acid ester, and containing variable amounts of other impurities (such as the above- 45 mentioned sodium chloride, sodium 1,2-dihydroxy propane- 3-sulphonate, or sodium 1-chloro-2-hydroxy propane-3-sulphonate) depending upon the thoroughness of the purification treatment to which it is subjected. The purified product is a dry powder nearly white in color, stable under 50 all ordinary conditions, and possessing in aqueous solution extraordinary foaming, emulsifying, wetting and cleansing properties, showing these properties strongly even in hard water.

60 The following examples will illustrate different methods of making the products of my invention, all quantities being by weight.

Example 1

180 parts of the sodium salt of glycerol sulphonic acid (sodium 1,2-dihydroxy propane-3-sulphonate, prepared by heating alpha chlorohydrin with aqueous Na_2SO_3 solution and subsequent removal of water) are heated at 150° to 225° C. for 6 hours with stirring with 210 parts of the 65 fatty acids from cocoanut oil, the water evolved

in the reaction being allowed to escape and the fatty acids being returned to the reacting chamber by suitable reflux condensation. The product of this reaction is then purified by washing with cold ethyl alcohol or other low-boiling alcohol, or preferably by dissolving in hot ethyl alcohol, filtering to remove insoluble inorganic salts, or other insoluble matter and crystallizing from the alcoholic solution. The product thus obtained is a nearly white dry powder, stable under 10 ordinary conditions of use, and possessing in aqueous solution extraordinary foaming, emulsifying, wetting and cleansing properties and can be used advantageously even in hard water.

5

Example 2

195 parts of the potassium salt of 1,2-dihydroxy propane-3-sulphonic acid are heated at 75° to 125° C. with stirring, for 10 hours with 300 parts of oleic acid chloride. The produce of the reaction is made neutral with NaOH , Na_2CO_3 , NH_3 or other suitable alkali and is then purified as in Example 1. The purified product has the properties described under Example 1.

25

Example 3

200 parts of the sodium salt of 1-chloro-2-hydroxy propane-3-sulphonic acid are heated at 100° to 200° C. with stirring for 5 hours with 300 parts of sodium soap prepared from tallow. The product of the reaction may then be purified as in Example 1, and it then possesses the properties described in Example 1.

35

Example 4

The triethanolammonium (sometimes called triethanolamine) compound may be formed as follows:

290 parts of the sodium salt of commercial stearic acid are heated at about 125° C., with stirring for 4 hours with 325 parts of the triethanolammonium salt of 1-chloro-2-hydroxy propane-3-sulphonic acid (prepared by heating 1,3 dichlorohydrin with triethanolaminium sulphite). The product of the reaction may be purified as in Example 1, and then possesses the properties described in Example 1.

45

Having thus described my invention, what I claim as new and desired to secure by Letters Patent is:—

50

1. A new composition of matter consisting of monohydric aliphatic alcohols derived from a soluble salt of 1,2-dihydroxy propane-3-sulphonic acid by esterification of one of its hydroxyl groups with a fatty acid containing at least six carbon atoms.

55

2. The process of preparing foaming, emulsifying, wetting and cleansing agents comprising chemically combining one molecular weight of a soluble salt of 1,2-dihydroxy propane-3-sulphonic acid with one molecular weight of a fatty acid having at least 6 carbon atoms.

60

3. The process of preparing foaming, emulsifying, wetting and cleansing agents comprising chemically combining one molecular weight of 1 halogen-2-hydroxy propane-3-sulphonic acid with one molecular weight of the alkali metal soap of a fatty acid having at least six carbon atoms.

65

4. Wetting, cleansing and emulsifying agents consisting of compounds of the general formula

70

where M may be an equivalent weight of any

alkali metal, alkaline earth metal, heavy metal, ammonium or basic organic radical which, in the above combination, is soluble in water and where one X is a hydroxyl group and the other X consists of the group RCOO , in which R is the alkyl radical of a fatty acid having at least six carbon atoms.

5. A new composition of matter consisting of compounds of the general formula

where M may be an equivalent weight of any alkali metal, alkaline earth metal, heavy metal, ammonium or basic organic radical which in the 15 above combination is soluble in water and where one X is a hydroxyl group and the other X consists of the group RCOO , in which R represents alkyl radicals of fatty acids derived from coconut oil.

20 6. The process which comprises causing a compound selected from the group consisting of 1,2-dihydroxy propane-3-sulphonic acid, 1 halogen-2-hydroxy propane-3-sulphonic acid, and the soluble salts of these compounds, to react with 25 a compound selected from the group consisting of fatty acids containing at least six carbon atoms per molecule, and their alkali metal salts.

7. The process which comprises causing a compound of the general formula

wherein M stands for an equivalent weight of any alkali metal, alkaline earth metal, heavy metal, ammonium or basic organic radical which in the 35 above combination is soluble in water, to react with a fatty acid whose molecule contains at least six carbon atoms.

8. The process which comprises causing a compound of the general formula

wherein X stands for a halogen atom and M stands for an equivalent weight of any alkali metal, alkaline earth metal, heavy metal, ammonium or basic organic radical which in the above combination is soluble in water, to react with an alkali metal salt of a fatty acid whose molecule contains at least six carbon atoms.

5 9. Wetting, cleansing and emulsifying agents consisting of the products formed by causing a 10 compound of the general formula

wherein M stands for an equivalent weight of any alkali metal, alkaline earth metal, heavy metal, ammonium or basic organic radical which in the 15 above combination is soluble in water, to react with a fatty acid whose molecule contains at least six carbon atoms, said products of reaction possessing great power to foam, emulsify, 20 wet, and cleanse, both in hard water and in soft water.

10 10. Wetting, cleansing and emulsifying agents consisting of the products formed by causing a 25 compound of the general formula,

wherein X stands for a halogen atom and M stands for an equivalent weight of any alkali metal, alkaline earth metal, heavy metal, ammonium or basic organic radical which in the 30 above combination is soluble in water, to react with an alkali metal salt of a fatty acid whose molecule contains at least six carbon atoms, said 35 products of reaction possessing great power to foam, emulsify, wet, and cleanse, both in hard water and in soft water.

CHARLES C. CLARK. 40

DISCLAIMER

2,006,309.—Charles C. Clark, St. Bernard, Ohio. HYDROXY SULPHONATED FATTY ACID ESTERS AND THEIR PRODUCTION. Patent dated June 25, 1935. Disclaimer filed December 18, 1935, by the assignee, *The Procter & Gamble Co.*

Hereby enters this disclaimer to the process of claim 6 in so far as such process comprises causing 1 : 2 dihydroxy propane 3-sulfonic acid to react with a compound selected from the group consisting of fatty acids containing at least six carbon atoms per molecule and their alkali metal salts, and in so far as such process comprises causing the soluble salts of 1 : 2 dihydroxy propane 3 sulphonic acid to react with a compound selected from the alkali metal salts of the group consisting of fatty acids containing at least six carbon atoms per molecule.
